COMBINATION MOTOR FOR ROTATING AND COLORING AN EGG, AND HOLDER THEREFOR

Stanley J. Fudro, % Fudro Products, Inc., Box 329,
Minneapolis, Minn.

Filed Jan. 6, 1965, Ser. No. 83,290

Term of patent 14 years

(Cl. D9—2)

FIG. 1 is a view in perspective of a combination motor for rotating and coloring an egg, and holder therefor, illustrating my new design;

FIG. 2 is a view in top plan thereof;

FIG. 3 is a view in side elevation thereof;

FIG. 4 is a view in bottom plan thereof; and

FIG. 5 is a view in front elevation thereof.

The broken line showing of the egg in FIG. 1 is for illustrative purposes only.

I claim:

The ornamental design for a combination motor for rotating and coloring an egg, and holder therefor, as shown and described.
